CLAIM

The ornamental design for a duffle bag, as shown and described.

DESCRIPTION

FIG. 1 is a front perspective view of the duffle bag showing the new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines depict portions of the duffle bag that form no part of the claimed design.

1 Claim, 4 Drawing Sheets
